UNITED STATES PATENT OFFICE.

HARRY W. FROST, OF DETROIT, MICHIGAN, ASSIGNOR TO CHICAGO RAILWAY EQUIPMENT COMPANY, OF CHICAGO, ILLINOIS, A CORPORATION OF ILLINOIS.

BRAKE-BEAM.

SPECIFICATION forming part of Letters Patent No. 729,924, dated June 2, 1903.

Application filed January 10, 1902. Serial No. 89,145. (No model.)

To all whom it may concern:

Be it known that I, HARRY W. FROST, a citizen of the United States, residing at Detroit, in the county of Wayne and State of Michigan, have invented certain new and useful Improvements in Brake-Beams, of which the following is a specification, reference being had therein to the accompanying drawings.

10 The invention relates to an improvement in beams and the process for making the same, especially intended for railway brace-beams, but which may be adapted for other uses; and it consists particularly in such a beam having reduced ends, such reduced ends being formed by cutting elongated notches or slots therein and then closing the slot, thereby reducing the width of the beam an amount equal to the width of the notch or 15 slot, all as more fully hereinafter described, and particularly pointed out in the claims.

In the drawings, Figure 1 is a plan view of my beam, showing it fitted for use as a brake-beam. Fig. 2 is a plan view of the end of 20 the beam, showing the notch or slot formed therein. Fig. 3 is a similar plan showing the slot closed and the end thereby reduced. Fig. 4 is a plan similar to Fig. 3, showing the 25 brake-head applied thereto. Fig. 5 is an end elevation of Fig. 4. Fig. 6 is a similar elevation of a slightly-modified form of beam.

A represents a straight solid beam, which in this instance in Figs. 1 to 5 I show provided with the flanges B B' at opposite edges, 30 forming what is commonly known as an I-beam.

In Fig. 6 I show the flange B in the shape of a bead or circular bar instead of a flat flange shown in the other figures. The detail of the cross-section of the beam is immaterial and depends upon the use and the strains to which it is to be subjected.

In making the beam, assuming that we use an I-beam to start with, I first cut out 40 of the web C between the flanges a piece of material, which will leave a notch or slot D in the end of the beam of a shape correspond-

ing to the shape which the finished beam is desired to have on its outer face. In this instance I show the slot as having the parallel 50 sides a the greater part of its length and the inclined side b at the inner end making a slot, the main portion of which is a parallelogram and the end portion of which is tapering, as clearly shown. The beam with the 55 ends thus notched or slotted is then subjected to pressure through any suitable dies or by rolling or other means, so as to close this notch or slot by abutting the two sides thereof and leaving simply a joint c at the point 60 of closure. It will be observed that this slot is formed close to the flange B', so that when the beam is reduced by the closing of the slot the joint will be in close proximity to the said flange. The effect of this operation 65 is to make a beam having its central portion or web of uniform width and its ends of reduced width, the thickness of the material in the web being unchanged and undeflected. The beam having these reduced ends may 70 be used for various purposes—such, for instance, as brake-beams—and in that case I apply to the reduced end portion of the beam 75 brake-heads E, apertured to fit the ends thereof and embrace the flange B', extending across the joint c and overlapping the web, as plainly shown in Figs. 5 and 6.

The brake-head may be secured to the beam by suitable means, such as a rivet or rivets F, passing through the web beyond the 80 joint, so that the fact that the beam is slit will not affect materially its strength.

It will be seen that by making the slot with the straight side a and the inclined side b and then closing the bifurcation or notch 85 the web will be formed with the inclined portions G at the point where the inclined side b is formed and that the ends will be straight, but reduced in width through the portion lettered H in Fig. 3.

90 What I claim as my invention is—

1. A railway brake-beam having marginal flanges and a central web, the web being continuous from end to end and of uniform

thickness having the tapering portion G and the reduced straight portion H.

2. A brake-beam having longitudinal marginal flanges, a connecting-web, and reduced ends formed by cutting notches D, the main portion of each of which is a parallelogram having its end portion tapered, and having the tongue with the straight side pressed into

the shape of the other side, substantially as described.

In testimony whereof I affix my signature in presence of two witnesses.

HARRY W. FROST.
